COMBINATION BEVERAGE KEG COOLER AND DISPENSER

James M. Kellum, St. Paul, and Eugene E. Bolkcom,
Minneapolis, Minn., assignors to Poly-Cron, Inc., St.
Paul, Minn., a corporation of Minnesota

Filed Oct. 22, 1963, Ser. No. 77,087

Term of patent 14 years

(Cl. D52—2)

FIG. 1

FIG. 2

FIG. 3

FIG. 4

FIG. 5

FIG. 6

FIG. 1 is a perspective view showing the front, one side and top of a combination beverage keg cooler and dispenser embodying the new design.

FIG. 2 is a top plan view.

FIG. 3 is a side elevational view.

FIG. 4 is a front elevational view.

FIG. 5 is a side elevational view opposite to the side shown in FIG. 3.

FIG. 6 is a rear elevational view.

We claim:

The ornamental design for a combination beverage keg cooler and dispenser, as shown and described.
